ABRADING MACHINE

Philip H. Hutchinson, Montclair, N. J., assignor
to General Motors Corporation, Detroit, Mich.,
a corporation of Delaware

Application December 10, 1935, Serial No. 53,771

28 Claims. (Cl. 51—112)

This invention relates to abrading machines and comprises all of the features of novelty herein disclosed. In a cylindrical roller bearing, the rollers are frequently restrained against endwise creep by flanges or the like on the race rings. It is highly desirable to have the rollers all of the same length with the end surfaces of each roller revolving in a plane exactly parallel to the guide flanges, or perpendicular to the roller axes, inasmuch as any wobble motion of the ends causes undue wear, noise and other undesirable effects including an impairment of thrust capacity.

An object of the invention therefore is to provide a precision end grinding machine for grinding rollers or the like to a precise length and with their end faces perpendicular to their axes. Another object is to provide a precision machine having improved means to guide and control a roller or the like as it is passed across an abrading member. Another object is to provide improved means to present articles to an abrading machine to the end that the articles will enter a grinding throat and pass through it in accurate position. Still another object is to provide means for insuring controlled rotation of a roller or the like as it is presented to an abrading member and to prevent the abrading member from taking control of the roller or getting it out of accurate position.

To these ends and also to improve generally upon devices of this character, the invention consists in the various matters hereinafter described and claimed. In its broader aspects, the invention is not necessarily limited to the specific construction selected for illustrative purposes in the accompanying drawings in which

Fig. 1 is a front elevation of the machine with portions in vertical section, the grinding wheels being omitted.

Fig. 2 is a side elevation, one of the grinding wheels being omitted.

Fig. 3 is an end view of a chute supporting bracket with the chute in section.

Fig. 4 is a cross sectional view of a portion of a rotary carrier or feed wheel, the section being taken on the line 4—4 of Fig. 5.

Fig. 5 is a side view of a portion of the carrier of Fig. 4.

Fig. 6 is a side view of a supporting standard.

Fig. 7 is a plan view of the standard.

Fig. 8 is a side view of a pressure shoe and its side guides.

Fig. 9 is an inside edge view of the device of Fig. 8 showing also one of its supporting studs.

Fig. 10 is a cross sectional view of the entrance guides taken about on the line 10—10 of Fig. 8.

Fig. 11 is a cross sectional view of the exit guides taken about on the line 11—11 of Fig. 8.

Fig. 12 is an inside view of a portion of the arcuate shoe and its entrance guides.

Fig. 13 is a longitudinal sectional view of the upper end portion of the shoe.

Fig. 14 is a cross sectional view similar to Fig. 10 but showing the shoe and guides adapted for 10 barrel rollers.

Fig. 15 is a plan view of a portion of a carrier with pockets adapted for barrel rollers.

Fig. 16 is a cross sectional view showing a barrel roller in grinding position between its pressure 15 shoe and its regulating wheel.

First outlining the general operation, elongated articles which are to be ground with the ends flat and parallel and at right angles to their axes (such as cylindrical or barrel-shaped rollers for 20 roller bearings) are fed sidewise down an inclined chute to notches in a rotary carrier, the rollers being then supported on the outer periphery of a work-rolling ring or regulating wheel which rotates at twice the speed of the carrier. As 25 the rollers travel between two opposed, radial faced grinding wheels which grind the ends, they are urged by an arcuate shoe against the periphery of the work-rolling ring or regulating wheel. The pressure of the rollers against the driven 30 work-rolling ring causes the rollers to rotate on their axes as they pass between the grinding wheels, and the rollers are kept from cocking or twisting with respect to the work-rolling ring by the notches in the carrier. The rollers travel between the work-rolling ring and the shoe in a 35 manner analogous to the travel of bearing rollers between an inner and an outer race ring, and the carrier acts somewhat like the separator of a roller bearing so that the grinding of the rollers occurs 40 under conditions corresponding to running conditions of such rollers in an actual bearing and great accuracy is assured.

The numeral 10 indicates a supporting platform secured by cap screws 12 to the base 14 of a 45 standard or web 16 having an enlargement or journal box 18. One end face of the latter has an annular recess 20 with a number of holes 22 for coil springs 24 which press against one side of a sealing ring 26. The ring is held from rotation by a pin 28 entering a hole 30 in the enlargement 18. The sealing ring presses laterally against a face plate or head 32 on a hollow sleeve 34 and excludes foreign matter from bearing bushings 36 and 38 which support the sleeve for rotation. 50 55

The face plate 32 has an annular recess for a sealing ring 40 which is urged by coil springs 42 against one side of a face plate or head 44 on the end of a shaft or spindle 46 which is journaled 5 for rotation in bearing bushings 48 of the sleeve 34.

To drive the shaft 46, a sprocket wheel 50 is keyed to it and is driven by a sprocket chain not shown from any suitable source, the chain being guided by an idler roll 54 rotatably mounted on 10 a stud 56 on a bracket 58 which is attached by screws 60 to the bottom of the platform 10. To drive the sleeve 34, a gear 64 is keyed to the shaft 46 between a thrust washer 66 and a spacer 68 and meshes with a larger gear 70 which is journaled 15 on a bearing bushing 72 on a supporting stud 74. A spacing sleeve 76 and a gear 78 are secured to the gear 70 by a pin 80, the gear 78 meshing with a gear 82 which is secured by a key 84 to the sleeve 34 between a thrust washer 20 86 and a clamping nut 88. The ratio of the gears is preferably so selected that the sleeve 34 is driven at just half the speed of the shaft 46. An oil cup 90 supplies oil to a port 92 communicating with radial ports 94 and an inclined port 96 to 25 lubricate the bearings.

A feed ring or carrier 100 is secured in a notch of the face plate 32 by screws 102 and a dowel pin 104 and has an overhanging rim 106 which is cut through at intervals to form notches or pockets 108 receiving the rollers R to be ground. The notches are substantially semi-circular but larger than the rollers to have a little clearance with the latter, each notch having a cut away forward edge 109 which facilitates entry of a roller from a feed chute. A work-rolling ring or regulating wheel 110 is secured in a notch of the face plate 44 by screws 112 and a dowel pin 114 and its periphery lies within the rim 106 to frictionally engage the middle portions of the rollers where the latter project through the notches or pockets 108. Fastened to a pad 116 on the standard 16 is a chute-supporting plate 118 having a raised lip 120 at one side and an upright 122 at the other side between which an inclined chute 124 is secured by a top clamping plate 126. The chute is U-shaped in cross section and has a cover plate 128. The rollers gravitate downwardly in the chute and enter sidewise one by one into the notches or pockets 108 as the carrier 100 rotates. 50 The rollers are thus carried upwardly between arcuate guides 130 which are welded to the side walls of the chute.

As the rollers are carried beyond the vertical center of the carrier 100, they enter between an 55 arcuate shoe 140 and the work-rolling ring or regulating wheel 110. The shoe 140 has its inner concave edge rigid and of unvarying radius. It is spring-pressed towards the rollers as will appear and has side rails 142 raised slightly above a central recess 144 so that the rollers only engage 60 near their ends with the shoe. Entrance guides 146 are secured to the sides of the shoe at the upper end thereof and exit guides 148 are secured to the sides of the shoe at the lower end thereof, 65 the guides in each case extending close to the periphery of the opposed grinding wheels G. The shoe and the guides have holes 150 and are loosely supported at each end on a stud 152 of smaller diameter than the hole 150, the shoe with its 70 guides being guided between a collar 154 and a washer 156 which is clamped by a nut against a shoulder on the stud. The stud has a supporting portion 158 adjustably fastened by set screws 160 in a horizontally elongated hole 160 of a 75 bearing lug 162 on the standard 16. This adjust-

ment is to position the shoe initially so it will have proper play on the stud 152. A pin 164 projects from each end of the shoe and is connected by a coil spring 166 to an adjusting screw 168. One of the screws 168 is threaded in a post 170 projecting from a lug 172 on the standard 16 and the other is threaded in a lug 174 of the platform 10.

The entrance end of the shoe has a rounded nose 174 (Fig. 13) and the entrance ends of the 10 guides 146 are flared as at 176. The guides are spaced a little wider apart than the rails 142 because the rollers must project beyond the latter to engage the radial faces of the grinding wheels G. One of the entrance guides 146 has a cut-out 15 portion 178 and in this is a movable jaw or guide 180 which is supported by a leaf spring 182 which urges such jaw towards the opposed entrance guide. This jaw will give if any roller is slightly longer than the others and insures the crowding 20 of one end of the roller against such opposed guide preparatory to engaging the grinding wheels. The movable jaw has a flared or bevelled face 184 to avoid any obstruction to entry of the roller. 25

As a roller is about to enter between the grinding wheels, it is rotated on its axis and bodily traversed between the arcuate shoe and the regulating wheel which form a controlling guide therefor, the entrance guides tending to hold the roller aligned crosswise. The rotary carrier and its pockets retard the advance of the roller and prevent the grinding wheels taking control as the first heavy cut occurs. The very important function of keeping the roller exactly at right 35 angles to the parallel, flat faces of the grinding wheels during grinding is produced by the three-point support afforded by the spaced rails 142 which engage the roller near the ends while the narrower ring or regulating wheel engages the 40 roller near the middle. The action is enhanced by having the radius of the shoe as small as is consistent with an ample travel of the roller while between the grinding wheels. In the illustrated construction, the roller has a sufficient 45 travel to make it turn on its axis at least twice and such rotation during grinding further insures that the opposite ends will be ground exactly parallel and at right angles to the axis. The rotating roller wipes all the way across the wheels 50 to the inner edges and then wipes back to the outer periphery so that the roller dresses the wheels and keeps them flat. Most of the time there is only one roller between the grinding wheels, or 55 between the shoe and the regulating wheel, and never more than two, this being due to the spacing of the roller pockets of the feed ring. Hence there is no chance for one or more intermediate and smaller rollers to be free from full control in respect to rotation on their axes, bodily travel 60 or location as they are pressed between the rigid edge of the shoe and the opposed edge of the regulating wheel. The exit portion of the shoe 140 is curved near the grinding wheels but merges 65 into a tangent which lets the finished roller drop out.

In operation, the rollers are fed down the chute 124 and fall one by one into the notches or pockets 108 of the rotary carrier 100. They pass 70 between the arcuate guides 130 and enter between the entrance guides 146. As they reach the movable jaw or guide 180 they are urged endwise against the opposed guide 146 to square them up for entry between the grinding wheel G. The grinding wheels attempt to carry the rollers 75

bodily but the carrier 100 restrains or retards them and regulates their passage. As the rollers enter between the wheels they are already rotating because they are urged by the spring-pressed 5 shoe 140 against the work-rotating ring 110 which turns at twice the speed of the carrier. The rollers must therefore roll on their axes as they pass between the wheels and as they wipe across the latter, first towards the center of the wheels 10 and then back to the outside. The three-point support of the rollers keeps them aligned and the turning of the rollers further insures the grinding of both ends perpendicular to their axes.

In Fig. 14, the shoe 190 is modified for convex 15 or barrel-shaped rollers, its edge 192 being concave and provided with a relief groove 194. Side guides 196 with a movable jaw 198 similar to the side guides 146 and movable jaw 188 are also employed. With rollers of this shape, it is also 20 desirable, as indicated in Fig. 15, to make the carrier 100 with pockets 200 which are curved to fit the rollers lengthwise, the rollers projecting through the rim of the carrier at the slots 202. The ring or regulating wheel 110 is preferably 25 straight crosswise to engage the curved rollers at the middle of their lengths. In the case of straight rollers, the narrow width of the wheel makes it engage the rollers only near their middle portions.

30 I claim:

1. In a device of the character described, a pair of members spaced apart to form a work-treating throat, at least one of said members being an abrading member, a driven regulating wheel having a smooth peripheral surface projecting into the throat to frictionally engage the periphery of a round work-piece, and a shoe extending between the members and having an arcuate edge substantially concentric with the 35 periphery of the regulating wheel to form therewith a guide for the work, the guide being open at the ends for admission and discharge of work-pieces, the wheel and the shoe frictionally engaging opposite sides of the work to cause the 40 work to turn on its axis and roll circumferentially of the regulating wheel, and means for feeding work-pieces into the guide in such spaced apart relation that the frictional engagement of the wheel and the shoe with the work is limited to 45 two work-pieces; substantially as described.

2. In a device of the character described, a pair of members spaced apart to form a work-treating throat, at least one of said members being an abrading member, a driven regulating wheel 50 having a smooth peripheral surface projecting into the throat to frictionally engage the periphery of a round work-piece, a pressure shoe extending between the members and having a rigid arcuate edge substantially concentric with the 55 periphery of the regulating wheel to form an arcuate work guide therewith, the guide being open at the ends for admission and discharge of work-pieces, means for feeding work-pieces in spaced relation to the guide, and means for urging the shoe yieldingly towards the regulating wheel to hold a work-piece against the latter and cause the work to turn on its axis and roll circumferentially of the regulating wheel; substantially 60 as described.

70 3. In a device of the character described, a pair of members spaced apart to form a work-treating throat, at least one of the members being an abrading member, a driven regulating wheel 65 projecting into the throat, a shoe curving about the periphery of the regulating wheel and urged

towards the latter, and a driven work-carrier projecting into the throat between the shoe and the regulating wheel; substantially as described.

4. In a device of the character described, a pair of members spaced apart to form a work-treating throat, at least one of the members being an abrading member, a driven regulating wheel 5 projecting into the throat, a shoe curving about the periphery of the regulating wheel, and a rotary work carrier having work-receiving 10 pockets movable through the throat and between the regulating wheel and the shoe; substantially as described.

5. In a device of the character described, a pair of members spaced apart to form a work-treating 15 throat, at least one of the members being an abrading member, a driven regulating wheel projecting into the throat, a shoe curving about the periphery of the regulating wheel, a work-carrier having a portion movable through the space between the regulating wheel and the shoe, and means for driving the work-carrier at half the speed of the regulating wheel; substantially 20 as described.

6. In a device of the character described, a pair of members spaced apart to form a work-treating throat, at least one of the members being an abrading member, a driven regulating wheel projecting into the throat, a shoe curving about the periphery of the regulating wheel, 25 a rotary work-carrier having work-receiving pockets distributed about the periphery of the regulating wheel and spaced apart at such angular distance that a maximum of two can be in the throat at one time, and means for driving the work carrier 30 at half the speed of the regulating wheel; substantially 35 as described.

7. In a device of the character described, a pair of members spaced apart to form a work-treating throat, at least one of the members being 40 an abrading member, a driven regulating wheel projecting into the throat, a shoe curving about the periphery of the regulating wheel, and the shoe having spaced side rails to coact with the periphery of the regulating wheel and form therewith a three-point support for the work; substantially 45 as described.

8. In a device of the character described, a pair of members spaced apart to form a work-treating throat, at least one of said members being an 50 abrading member, and means for guiding a round work-piece through the throat with its axis perpendicular to the abrading member, said means comprising a regulating wheel with a smooth cylindrical periphery and a shoe having an 55 arcuate work engaging surface of unvarying radius substantially concentric with and opposed to the periphery of the regulating wheel to cause an interposed work-piece to roll on the regulating wheel circumferentially thereof, one of said last 60 named parts engaging the work-piece near the ends thereof and the other engaging the work-piece near the middle; substantially as described.

9. In a device of the character described, a pair of members spaced apart to form a work-treating throat, at least one of said members being an abrading member, and means for guiding a round work-piece through the throat with its axis perpendicular to the members, said means comprising a narrow regulating wheel to engage 70 the middle portion of the work-piece, and a shoe curved about the periphery of the regulating wheel and having spaced rails engaging the work-piece near the end portions thereof; substantially 75 as described.

10. In a device of the character described, a pair of members spaced apart to form a work-treating throat, at least one of said members being an abrading member, and means for passing a round work-piece bodily through the throat, while turning the work-piece on its axis, said means comprising a driven regulating wheel, an arcuate shoe having a surface substantially concentric with the regulating wheel, and a driven carrier having work-receiving pockets providing for free rotation of the work on its axis but retarding bodily movement of the work when the work is engaged by the abrading member; substantially as described.
- 15 11. In a device of the character described, a pair of members spaced apart to form a work-treating throat, at least one of said members being an abrading member, and means for causing a round work-piece to pass bodily through the grinding throat while turning on its axis, said means comprising a driven regulating wheel, an arcuate shoe having a surface substantially concentric with the regulating wheel, a driven carrier having pockets rotatably supporting the work-piece, means for driving the carrier at half the speed of the regulating wheel, and means for causing a yielding movement of approach between the shoe and the regulating wheel; substantially as described.
- 20 12. In a device of the character described, a pair of members spaced apart to form a work-treating throat, at least one of said members being an abrading member, and a driven work-carrier for presenting round work-pieces to the throat and controlling passage through the throat, said carrier having open work-receiving pockets spaced apart and movable through the throat for supporting the work-pieces for free rotation on their axes while being ground, the pockets being so spaced that a maximum of two with their contained work-pieces can be in the throat at one time, and means extending into the throat for compelling the work-pieces to turn constantly on their axes; substantially as described.
- 25 13. In a device of the character described, a pair of members spaced apart to form a work-treating throat, at least one of said members being an abrading member, a driven regulating wheel having a smooth periphery with a portion of its periphery in the throat, a shoe having an arcuate guiding surface substantially concentric with the regulating wheel to form a work guide therewith, the guide being open at one end of the shoe to admit work-pieces thereto, and a spring 30 for urging the shoe towards the regulating wheel to cause interposed work to turn on its axis and roll circumferentially of the driven regulating wheel; substantially as described.
- 35 14. In a device of the character described, a pair of members spaced apart to form a work-treating throat, at least one of said members being an abrading member, a driven regulating wheel having a smooth work-engaging periphery with a portion of its periphery in the throat, a shoe having a rigid arcuate guiding surface of unvarying radius substantially concentric with and opposed to the periphery of the regulating wheel where such periphery projects into the throat, supporting studs for the ends of the shoe 40 and providing lost motion therefor, and springs for urging the shoe towards the regulating wheel and against the interposed work whereby the work is caused to roll circumferentially of the regulating wheel; substantially as described.
- 45 15. In a device of the character described, a pair of members spaced apart to form a work-treating throat, at least one of said members being an abrading member, a rotary work-carrier for presenting work-pieces to the throat and controlling the passage thereof through the throat, said carrier projecting into the throat and having work-receiving pockets, and relatively rotatable work-engaging members for rolling the work-pieces on their axes as they pass through the throat, said work-engaging members having work-engaging surfaces concentric to one another and to the carrier and also projecting into the throat; substantially as described.
- 50 16. In a device of the character described, a pair of members spaced apart to form a work-treating throat, at least one of said members being an abrading member, relatively rotatable work-engaging members for rolling work-pieces on their axes as they pass through the throat, said relatively rotatable work-engaging members 55 projecting into the throat and comprising an arcuately concave member opposed to and concentric with an arcuately convex member, and means for preventing the abrading member from taking control of the passage of the work-pieces through the throat; substantially as described.
17. In a device of the character described, a pair of members spaced apart to form a work-treating throat, at least one of said members being an abrading member, relatively rotatable work-engaging members concentric with one another and providing an arcuate channel for rolling work-pieces on their axes before they reach the throat, and a driven carrier having work-receiving pockets for retarding movement of the work-pieces when they are engaged by the abrading member; substantially as described.
18. In a device of the character described, a pair of members spaced apart to form a work-treating throat therebetween, at least one of said members being an abrading member, and means for guiding work-pieces to the throat comprising a friction wheel and a shoe having an arcuate edge concentric therewith, a portion of said concentric edge being outside of the throat, a side 60 guide extending into close proximity to the abrading member and alongside the periphery of the friction wheel, and a spring pressed guide opposed to said side guide for urging a work-piece against the latter; substantially as described.
19. In a device of the character described, a pair of members spaced apart to form a work-treating throat therebetween, at least one of said members being an abrading member, and means for guiding work-pieces to the throat comprising concentric members for frictionally engaging the work both inside and outside the throat, a side guide extending into close proximity to the abrading member and alongside the space between the concentric members, and a guide 65 opposed to said side guide and comprising a fixed section and a spring pressed section; substantially as described.
20. In a device of the character described, a pair of members spaced apart to form a work-treating throat therebetween, at least one of said members being an abrading member, a rotary work-engaging wheel having a smooth periphery with a portion of its periphery projecting into the throat between said spaced members, a side guide extending into close proximity to the abrading member and along the periphery of the wheel, a shoe having an arcuate edge concentric with the wheel periphery, a portion of said concentric edge being between the 70
- 75 15. In a device of the character described, a

- members and another portion projecting therefrom, and a spring pressed guide opposed to said side guide for urging a work-piece against the latter; substantially as described.
5. 21. In a device of the character described, an abrading member, a driven regulating wheel projecting across and overlapping the abrading member, a rotary carrier having a rim portion projecting over and surrounding the periphery 10 of the regulating wheel, and the projecting rim of carrier having work-receiving pockets; substantially as described.
15. 22. In a device of the character described, an abrading member, a driven regulating wheel projecting across and overlapping the abrading member, a rotary carrier having a rim portion projecting over and surrounding the periphery of the regulating wheel and provided with work-receiving pockets which break through to the 20 regulating wheel, and means for urging the work-pieces against the wheel; substantially as described.
25. 23. In a device of the character described, an abrading member, a rotary regulating wheel and a rotary carrier each having portions of its periphery projecting across and overlapping the abrading member, and driving gearing interposed between the wheel and the carrier for positively driving one at a different speed from the other; 30 substantially as described.
35. 24. In a precision end grinding machine, a pair of grinding wheels spaced apart to form a grinding throat, and means for causing a round work-piece to pass bodily through the throat while turning on an axis perpendicular to the wheels, said means comprising a driven regulating wheel projecting into the throat and between the wheels, means for urging the work-piece against the regulating wheel, and a driven carrier having an open work-receiving pocket supporting the work 40 for free rotation, said urging means being non-rotary and concentric with the regulating wheel; substantially as described.
45. 25. In a precision end grinding machine, a pair of parallel, flat faced grinding wheels, and means for traversing round work-pieces bodily between the wheels while rotating each work-piece on an axis perpendicular to the grinding wheels, said means comprising relatively rotatable arcuate members having rigid and substantially concentric edges engaging the periphery of the work-piece and pressing the work-piece between them to insure rotation of the work-piece on its axis with bodily translation thereof, 50 said arcuate members extending partly within and partly without the space between the wheels,

and means for introducing work-pieces between the arcuate members at intervals to effect spacing of the work-pieces; substantially as described.

26. In a precision end grinding machine for round work, a pair of grinding wheels having 5 annular grinding surfaces parallel to one another to grind the ends of the work, a driven regulating wheel having a smooth peripheral edge projecting between the wheels, a rigid shoe having an arcuate edge projecting across the annular grinding surfaces from the outer periphery to the inner one and back to the outer periphery, 10 said arcuate edge being of unvarying radius concentric with the periphery of the regulating wheel, means for pressing said shoe towards the regulating wheel to frictionally grip the periphery of the work between said arcuate edge and the edge of the regulating wheel, and means for introducing work-pieces at such intervals as to limit contact of said edges to two work-pieces; substantially as 15 described.

27. In a precision end grinding machine for round work, a pair of parallel members spaced apart to form a grinding throat of uniform width, at least one of the members being a grinding 25 wheel, a driven regulating wheel having a smooth peripheral surface projecting into the throat, an arcuate shoe in the throat and having a rigid concave edge of unvarying radius curved about and opposed to the periphery of the regulating 30 wheel to form an arcuate work guide therewith, means for pressing the shoe and the regulating wheel one towards the other to frictionally grip the periphery of the work-pieces, and means for insuring a spacing of the work-pieces in the 35 guide such that the frictional gripping is limited to two work-pieces; substantially as described.

28. In a precision end grinding machine for round work, a pair of parallel members spaced apart to form a grinding throat of uniform width, 40 at least one of the members being a grinding wheel, a driven regulating wheel having a smooth peripheral surface projecting into the throat, an arcuate shoe in the throat and having a concave edge curved about and opposed to the peripheral 45 surface of the regulating wheel to form an arcuate work guide therewith, means for urging the shoe and the regulating wheel one towards the other to yieldingly grip work-pieces between them and cause rotation of the work, and means for 50 feeding work-pieces to the guide in such spaced relation that all work-pieces therein will be in pressure engagement with the shoe and the regulating wheel; substantially as described.

PHILIP H. HUTCHINSON.
